UNITED STATES PATENT OFFICE

2,330,885

SHOE PRESSING MACHINE

Fred V. Hart, Lynn, Mass., assignor to United Shoe Machinery Corporation, Flemington, N. J., a corporation of New Jersey

Application September 30, 1942, Serial No. 460,187

17 Claims. (Cl. 12—33)

This invention relates to machines for applying pressure to the bottoms of shoes and more particularly to means for supporting the shoe in the pressure-applying operation, the term "shoe" being generally used herein with reference to a shoe mounted on a last. The invention is illustrated as applied to a leveling machine of the so-called direct-pressure type such as shown, for example, in Letters Patent of the United States No. 1,275,562, granted August 13, 1918 on an application filed in the names of A. E. Jerram and J. Gouldbourn. It is to be understood, however, that the invention is not limited to machines of this type but is applicable generally to various kinds of machines for applying pressure to shoe bottoms, including machines for laying soles. Machines of the type illustrated in the above-mentioned patent are intended either to level the bottoms of shoes off a last, the machine being provided with a metal form to support the shoe in the pressure-applying operation, or, when provided with special fittings for the purpose, to level the bottom of a shoe on a last. These special fittings include toe and heel rests arranged to support the toe portion of a shoe and the heel portion of the last. It has been found necessary, particularly when operating on shoes supported on jointed lasts, to provide an additional support for that portion of the shoe between the heel end and the forepart to prevent distortion of the last and consequent damage to the shoe during the leveling operation.

An object of the present invention is to provide in a shoe-bottom-pressing machine an improved automatically operated means for supporting the shoe between the heel end and the forepart during the pressing operation. To this end and as a feature of the invention, the machine is provided with an additional supporting means which is automatically moved from an inoperative position into a shoe-supporting position in response to movement of the shoe-supporting jack from a loading position toward operating position. As illustrated herein, the additional shoe-supporting means comprises two supporting members engageable with opposite sides of the shoe between the heel end and the forepart. During movement of the jack toward operating position, the supporting members are moved inwardly into engagement with the opposite sides of the shoe under spring pressure. Associated with the means for moving the supports into engagement with the shoe are means for positively locking the supporting members in whatever position they are moved under pres-

sure. In the illustrated embodiment of the invention these supporting members are carried at the upper ends of links, the lower ends of which are pivoted to the jack. Also connected to the upper end of each link is an arm, the lower end of which is arranged to move in a cam track. Springs act upon these arms to move their lower ends outwardly and urge the links inwardly to carry the supporting members into engagement with the shoe in response to movement of the jack toward operating position. The lower end of each arm rides up its cam track and forms means for positively locking the associated supporting member in engagement with the shoe.

The above and other features of the invention, including various details of construction and combinations of the parts, will now be more particularly described by reference to the accompanying drawings and pointed out in the claims.

20 In the drawings,

Fig. 1 is a perspective view of the head of a machine in which the invention is embodied.

Fig. 2 is a side elevation of one of the shoe supporting jacks as viewed from the right of Fig. 1;

Fig. 3 is an end elevation of one of the shoe-supporting jacks looking from the toe end, certain parts being omitted; and

30 Fig. 4 is a section on the line IV—IV of Fig. 3. As illustrated herein, the invention is applied to a two-station, direct-pressure leveling machine having a pair of jacks 10 comprising posts 12 supported in carriers 14 movable from a vertical loading position as shown at the right in Fig. 1 into an inclined pressure-applying position as shown at the left in Fig. 1. The jacks are alternately swung into pressure-applying positions in which the bottom of a shoe carried thereby is positioned to be engaged by one of a pair of pressing forms 16 carried by a head 18. After the shoe has been moved into position to be engaged by a pressing form 16, the head 18 is moved by mechanism illustrated in the Jerram et al. patent, referred to above, to apply heavy pressure to the bottom of the shoe. After the head has been so moved, the bottom of the shoe is leveled by an oscillatory movement of the jack about an axis lying substantially in the tread surface of the sole.

35 The jacks are fitted to support a shoe on a last and each includes a base member 20 secured by screws 22 to the upper end of a post 12. The base member 20 carries means for supporting the forepart of a shoe and the heel end of a last

55

and additional supports for the shoe between the heel end and forepart.

The toe-supporting means illustrated herein is generally the same as that disclosed in Letters Patent of the United States No. 1,962,141 granted June 12, 1934 upon an application filed in the name of A. Eppler and comprises a member 24 (Fig. 2) adjustable in guideways 28 secured to the top surface of the base member 20. Mounted on the member 24 is a block 28 arranged to be adjusted vertically by means of a wedge 30. The wedge is adjusted by means of a screw 32 threaded into the wedge and having a handle 34 (Fig. 4) secured to its outer end for turning it. Collars 36 secured to the screw 32 engage opposite faces of a bracket 38 secured to the member 24 and prevent lengthwise movement of the screw so that the wedge is moved in or out with respect to the block 28 as the screw is turned thereby to raise or lower the block. Supported on the block 28 is a toe rest 40 comprising a rubber pad 42 hollowed out to receive the toe end of the shoe and a holder 44 on which the pad is mounted. The holder 44 is so mounted on the block 28 as to permit it to adjust itself to the shoe about an axis extending laterally of the shoe and located substantially at the shoe-engaging face of the pad 42.

The heel-supporting means comprises a block 46 adjustable toward and away from the toe rest in guides 48 secured to the upper surface of the base member 20. Between arms 50 secured to opposite sides and extending upwardly from the block 46 is pivoted at 51 a support 52 for a spindle 54 arranged to engage the spindle hole in the heel end of the last. In order to hold the shoe firmly on the jack, means are provided for swinging the support 52 for the spindle 54 in a clockwise direction, as viewed in Fig. 2, to cause the toe end of the shoe to be forced firmly against the toe pad 42. For this purpose a vertically movable rod 56 is threaded into the block 46 and is arranged to engage the support 52 to the left of the pivot 51. A spring 57 seated in a bore in the block engages the underside of the support 52 at the opposite side of the pivot 51 to hold the support against the rod 56. Splined to the lower end of the rod 56 is a spiral gear 58 which meshes with a spiral gear 60 carried by a shaft 62. The outer end of the shaft 62 is provided with a handle 64 by which the shaft may be turned in a direction to rotate the rod 56 and to move it upwardly by reason of its threaded connection with the block 46 thereby causing the shoe to be held firmly against the toe support.

For moving the heel and toe supports toward and away from each other a screw 66 provided with a handle 67 is threaded through the block 46 of the heel support and into the member 24 carrying the toe support, the screw being threaded oppositely at each end so that upon turning it the heel and toe supports are moved in opposite directions so that their relative positions may be adjusted for different sizes of shoes. Endwise movement of the screw 66 is prevented by a collar 68 secured to the screw between the heel and toe supports and projecting into a recess 70 (Fig. 2) formed in the base member 20.

In order to support the shoe between the heel and toe supports, thereby to prevent distortion of the last by which the shoe is carried with consequent damage to the shoe during the leveling operation, additional supporting members 72 are provided for engagement with opposite sides of the shoe. These supporting members each 75

comprises a U-shaped plate 74 covered by a piece of leather or other suitable material 76 of such a character that no damage will be caused to the shoe when it is engaged by these supporting members. The plates 74 are pivoted at 78 to the upper end of links 80, the lower ends of which are pivoted at 81 to a bracket 82 secured to the upper surface of the base member 20. Also connected to the links 80 by the pivots 78 are arms 84, the lower ends of which are engageable with the cam surfaces 86 of cam members 88 secured to the top of the base member 20. The arms 84 are formed with laterally extending projections 90 to the outer end portions of which are pivoted spring-retaining members 92 arranged to be engaged by the upper ends of compression springs 94, the lower ends of which seat in recesses formed in the base member 20. The cam surfaces 86 are so shaped as to prevent relative swinging of the arms 84 and 80 about the pivot 78 by the springs 94 when the lower ends of the arms 84 are in engagement with the cam surfaces. Consequently, the springs 94 act to swing the arms 84 and 80 inwardly about the pivots 81 to cause the supporting members 72 to engage the shoe. During this combined swinging movement of the arms 84 and 80, the arms 84 are swung by the springs 94 relatively to the arms 80 about the pivots 78 to maintain their lower ends in engagement with the cam surfaces 86 thereby causing the parts to be locked by the cams against outward movement in whatever positions they assume when the supporting members 72 engage the shoe.

When the jacks are in their loading positions, the supports 72 are held apart in inoperative positions so as not to interfere with the proper and rapid loading of a shoe on the jack. Extending upwardly through the springs 94 and the spring-retaining members 92 are rods 100 on the upper ends of which collars 102 are held by nuts 104. The lower ends of these rods pass through slots 105 in the base member 20 and through openings in the rearward ends of arms 106 carried by a shaft 108 journaled in brackets 110 depending from the forward portion of the base member 20. The lower ends of the rods 100 are provided with collars 112 underlying the adjacent ends of the arms 106 so that upon downward movement of these arms the rods 100 are caused to move downwardly and exert a downward force upon the lateral extensions 90 of the arms 84 in opposition to the upward force exerted by the springs 94. Integral with one of the arms 106 is a second arm 114 carrying a cam roll 116 engageable with the under surface of an inclined cam plate 118 secured to the frame of the machine. This cam plate is inclined upwardly and rearwardly so that the cam roll 116 is caused to move downwardly as the jack moves into loading position. This causes the shaft 108 to turn in such a direction as to move the rearward ends of the arms 106 downwardly to exert a downward pull on the rods 100 thereby moving the lower ends of the arms 84 inwardly and the upper ends of the arms outwardly as permitted by the shape of the cam 86 to carry the supports 72 out of engagement with the shoe.

After a shoe has been placed on the heel and toe supports and the heel support has been operated to force the forepart of the shoe firmly against the toe support, the jack is caused to move from its vertical position rearwardly into an inclined position to move the shoe into position to be operated upon by a pressing form 16.

As the jack thus moves, the arm 114 is permitted to be moved upwardly by reason of the upwardly inclined surface of the cam plate 118 until the springs 94 become effective to move the extensions 90 of the arms 84 upwardly, thereby to carry the supports 72 into engagement with the shoe. These supports are thus moved into engagement with the shoe under spring pressure before the jack has completed its rearward movement and the lower ends of the arms 84 are moved outwardly and by reason of their engagement with the cam surfaces 86 they positively lock the supports in the positions into which they have been moved by the springs 94. The movement of the supports 72 is entirely automatic and takes place as the jack moves from loading position toward operating position, and adequate support is provided for that portion of the last between the heel and toe ends to prevent any distortion thereof during the leveling operation. At the completion of the leveling operation, the jack is returned to loading position, during which time the cam roll 116 is moved downwardly by its engagement with the cam plate 118 so that the rods 100 are again pulled downwardly to move the arms 84 oppositely to the direction in which they are moved by the springs 94, thereby causing the supports 72 to be retracted, permitting ready removal of the shoe from the jack and loading of another shoe thereon.

Having thus described my invention, what I claim as new and desire to secure by Letters Patent of the United States is:

1. In a shoe-pressing machine, means for applying pressure to the bottom of a shoe, means for supporting a shoe at the heel end and at the forepart in the pressing operation, an additional support for the shoe between the heel end and the forepart, means mounting said additional support for movement into and out of engagement with a shoe on the supporting means, and means for moving said additional support into engagement with the shoe in response to movement of said supporting means toward operative position.

2. In a shoe-pressing machine, the combination with means for pressing the bottom of a shoe, of means for supporting the shoe at the heel end and at the forepart in the pressing operation, said shoe-supporting means being movable from a shoe-receiving position into position to present the shoe in operative relation to said bottom-pressing means, an additional support for the shoe between the heel end and the forepart, and means for moving said additional support automatically from an initial inoperative position into engagement with each shoe on said supporting means in response to the movement of the supporting means to present each shoe in operative relation to the bottom-pressing means.

3. In a shoe-pressing machine, the combination with means for pressing the bottom of a shoe, of means for supporting the shoe at the heel end and at the forepart in the pressing operation, said shoe-supporting means being movable from a shoe-receiving position into position to present the shoe in operative relation to said bottom-pressing means, additional supporting means for the shoe including members movable independently into engagement with each shoe at its opposite sides between the heel end and the forepart, and automatic means for thus moving said additional supporting members in response to the movement of said supporting means into operative relation to the bottom-pressing means.

4. In a shoe-pressing machine, means for ap-

plying pressure to the bottom of a shoe, means for supporting a shoe at the heel end and at the forepart in the pressing operation, an additional support for the shoe between the heel end and the forepart, means mounting said additional support for movement into and out of engagement with a shoe on the supporting means, means for moving said additional support into engagement with the shoe in response to movement of said supporting means toward operative position, and means for locking said additional support in engagement with the shoe.

5. In a shoe-pressing machine, means for applying pressure to the bottom of a shoe, means for supporting a shoe at the heel end and at the forepart in the pressing operation, an additional support for the shoe between the heel end and the forepart, means mounting said additional support for movement into and out of engagement with a shoe on the supporting means, means for moving said additional support into engagement with the shoe in response to movement of said supporting means toward operative position, means for locking said additional support in engagement with the shoe, and means for releasing said locking means and moving said additional support out of engagement with the shoe in response to movement of the supporting means into loading position.

6. In a shoe-pressing machine, means for applying pressure to the bottom of a shoe, means for supporting a shoe at the heel end and at the forepart in the pressing operation, an additional support for the shoe between the heel end and the forepart, spring means for urging said additional support into engagement with the shoe, and means for rendering said spring means effective in response to movement of said supporting means toward operative position.

7. In a shoe-pressing machine, means for applying pressure to the bottom of a shoe, means for supporting a shoe at the heel end and at the forepart in the pressing operation, an additional support for the shoe between the heel end and the forepart, spring means for urging said additional support into engagement with the shoe, means for rendering said spring means effective in response to movement of said supporting means toward operative position, and means for automatically locking said additional support in whatever position it is moved by the spring means.

8. In a shoe-pressing machine, means for applying pressure to the bottom of a shoe, a jack for supporting the shoe in the pressing operation, said jack including supports for the heel end and the forepart of a shoe and additional supports engageable with opposite sides of the shoe between the heel end and the forepart, means mounting said additional supports for movement into and out of engagement with a shoe on the jack, and means operative in response to movement of said jack toward operative position for moving said additional supports into engagement with the shoe.

9. In a shoe-pressing machine, means for applying pressure to the bottom of a shoe, a jack for supporting the shoe in the pressing operation, said jack including supports for the heel end and the forepart of a shoe and additional supports engageable with opposite sides of the shoe between the heel end and the forepart, means mounting said additional supports for movement into and out of engagement with a shoe on the jack, means operative in response

to movement of said jack toward operative position for moving said additional supports into engagement with the shoe, and means for locking said additional supports in engagement with the shoe.

10. In a shoe-pressing machine, means for applying pressure to the bottom of a shoe, a jack for supporting the shoe in the pressing operation, said jack including supports for the heel end and the forepart of a shoe and additional supports engageable with opposite sides of the shoe between the heel end and the forepart, spring means for urging said additional supports into engagement with the shoe, and means for rendering said spring means ineffective until the jack has been moved out of loading position to carry the shoe toward the pressure-applying means.

11. In a shoe-pressing machine, means for applying pressure to the bottom of a shoe, a jack for supporting the shoe in the pressing operation, said jack including supports for the heel end and the forepart of a shoe and additional supports engageable with opposite sides of the shoe between the heel end and the forepart, spring means for urging said additional supports into engagement with the shoe, means for rendering said spring means ineffective until the jack has been moved out of loading position to carry the shoe toward the pressure-applying means, and means associated with said additional supports for locking them in whatever position they are moved by said spring means.

12. In a shoe-pressing machine, means for applying pressure to the bottom of a shoe, means for supporting a shoe at the heel end and at the forepart in the pressing operation, an additional support for the shoe between the heel end and forepart, means mounting said additional support for movement toward and away from a shoe on the supporting means, an arm pivotally connected to said additional support, a spring connected to said arm to urge the additional support toward the shoe, and means cooperating with said arm for locking it in whatever position it is moved by said spring.

13. In a shoe-pressing machine, means for applying pressure to the bottom of a shoe, means for supporting a shoe at the heel end and at the forepart in the pressing operation, an additional support for the shoe between the heel end and forepart, means mounting said additional support for movement toward and away from a shoe on the supporting means, an arm pivotally connected to said additional support, a spring connected to said arm to urge the additional support toward the shoe, means cooperating with said arm for locking it in whatever position it is moved by said spring, and means for holding said additional support in inoperative position when the shoe-supporting means is in loading position.

14. In a shoe-pressing machine, means for applying pressure to the bottom of a shoe, a jack for supporting the shoe in the pressing operation, said jack including supports for the heel end and the forepart of the shoe and additional supports

engageable with opposite sides of the shoe between the heel end and the forepart, links carrying said additional supports for movement toward and away from a shoe on the jack, arms pivoted to said links, springs acting on said arms to move the links and the additional supports toward the shoe, and fixed cam members cooperating with said arms to lock them in whatever position they are moved by the springs.

15. In a shoe-pressing machine, means for applying pressure to the bottom of a shoe, a jack for supporting the shoe in the pressing operation, said jack including supports for the heel end and the forepart of the shoe and additional supports engageable with opposite sides of the shoe between the heel end and the forepart, links carrying said additional supports for movement toward and away from a shoe on the jack, arms pivoted to said links, springs acting on said arms to move the links and the additional supports toward the shoe, fixed cam members cooperating with said arms to lock them in whatever position they are moved by the springs, and means rendering said springs ineffective and holding said additional supports in inoperative positions when the jack is in loading position.

16. In a shoe-pressing machine, means for applying pressure to the bottom of a shoe, a jack for supporting the shoe in the pressing operation, said jack including supports for the heel end and the forepart of the shoe and additional supports engageable with opposite sides of the shoe between the heel end and the forepart, links carrying said additional supports for movement toward and away from a shoe on the jack, arms pivoted to said links, springs acting on said arms to move the links and the additional supports toward the shoe, fixed cam members cooperating with said arms to lock them in whatever position they are moved by the springs, and means operative in response to movement of the jack into loading position for moving said additional supports away from the shoe and for holding them in inoperative positions.

17. In a shoe-pressing machine, means for applying pressure to the bottom of a shoe, a jack for supporting the shoe in the pressing operation, said jack including supports for the heel end and the forepart of the shoe and additional supports engageable with opposite sides of the shoe between the heel end and the forepart, links carrying said additional supports for movement toward and away from a shoe on the jack, arms pivoted to said links, springs acting on said arms to move the links and the additional supports toward the shoe, fixed cam members cooperating with said arms to lock them in whatever position they are moved by the springs, a cam-operated lever carried by the jack and connected to said arms for moving them against the force of the springs to carry the additional supports away from the shoe, and a fixed cam member carried by the machine and cooperating with said lever to cause movement of said additional supports away from the shoe in response to movement of the jack into loading position.

FRED V. HART.
